DESIGN FOR A CHAIR

Willard H. Bond, Jr., East Grand Rapids, Mich.,
assignor to American Seating Company, Grand Rapids, Mich., a corporation of New Jersey

Application September 16, 1938, Serial No. 79,941

Term of patent 14 years

To whom it may concern:

Be it known that I, Willard H. Bond, Jr., a citizen of the United States, residing at East Grand Rapids, in the county of Kent and State of Michigan, have invented a new, original, and ornamental Design for a Chair, of which the following is a specification, reference being had to the accompanying drawing, forming a part thereof, in which:—

Figure 1 is a perspective view of the chair showing my new design, the distinguishing, essential and dominating feature or characteristic of the design being the end standards of the chair shown in full lines, the form and contour of the back, seat and arm rests being shown in dotted lines and indicating unimportant features of the design; and

I claim:

The ornamental design for a chair, as shown and described.

WILLARD H. BOND, JR.
